(57) **CLAIM**

The ornamental design for a base slat for a rolling shutter system, as shown and described.

DESCRIPTION

FIG. 1 is an end view of a base slat for a rolling shutter system showing our new design/ the opposite end view being a mirror image

FIG. 2 is a perspective front view thereof; and,

FIG. 3 is a perspective back view thereof.

The characteristic feature of the design resides in the outer silhouette of the profile.
